UNITED STATES PATENT OFFICE.

EDOUARD VEDOVELLI, OF PARIS, FRANCE.

RELAY.

1,417,785.

Specification of Letters Patent. Patented May 30, 1922.

Application filed July 16, 1920. Serial No. 396,792.

To all whom it may concern:

Be it known that I, EDOUARD VEDOVELLI, a citizen of the Republic of France, residing at Paris, France, have invented certain new and useful Improvements in Relays, (for which I have filed an application in France December 20, 1918, Patent No. 524124), of which the following is a specification.

10 The present invention relates to an apparatus functioning as a relay and designed to produce a contact or to effect a mechanical releasing action when an electric current of suitable intensity has passed 15 through it for a certain time.

An embodiment of the invention is illustrated diagrammatically in the accompanying drawing, in which—

20 Figure 1 is a view partly in elevation and partly in vertical section, and

Fig. 2 shows a modification of a detail.

Fig. 3 is a sectional view of the line 3—3, Fig. 1.

25 The apparatus comprises essentially a solenoid 1 through which the operating current flows. The current enters through one wire 2 and leaves by way of a small commutator 3 which enables a greater or smaller number of turns to be cut in. The 30 turns are distributed in such a way that the flux produced is always proportional to the intensity of the current and to the number of turns. Under these conditions the commutator 3 can serve to regulate the 35 intensity at which the control is produced. A soft iron core 4 works in the solenoid and is capable of being attracted when the number of ampere-turns is sufficient.

40 Below the core there is arranged a receptacle 5 of cast iron or other material unattackable by mercury. This receptacle communicates with another receptacle 6 in which there is arranged a plunger 7 operated by a regulating screw 8. The bottoms 45 of the two receptacles are filled with mercury so that the screw 8 when rotated enables the level of the mercury in the main receptacle 5 to be varied at will the receptacles 5 and 6 having a connecting passage 50 6^a through which the mercury flows. Within the interior of the receptacle 5 is arranged a cup 9 of thin sheet iron, fastened to the core by a rigid connecting rod 10. This cup is provided with an opening 11

in its lower portion, and the weight of 55 the unit comprised by the core, the connecting rod and the cup 9 is greater than the hydrostatic pressure of the mercury on the cup so that the latter is immersed in the mercury, the mercury passing into its interior through the opening 11 and rising to the same level on the inside of the cup as on the outside. The opening 11 is capable of being plugged or partially closed by an iron valve 12 which is elliptical in 60 cross section at its portion which engages the opening 11; but the valve, owing to its lesser density, tends to float and is therefore forced downward by a stem or needle 13 on which is fastened a weight 14 65 slightly in excess of the pressure exerted by the mercury on valve 12. The opening 11, because of its shape is never entirely closed by the valve 12, so that when the valve is seated the mercury may flow in a small jet 70 or stream from the inside of the cup to the outside thereof or vice versa.

75 The operation is as follows: Under normal conditions, the number of ampere-turns is insufficient to effect an attraction of the 80 movable core unit, but as the number of turns increases, the core is attracted; however, in order to raise it, it is necessary to dispose of the mercury in the cup. For 85 this purpose mercury flows out through the part of the opening 11 not closed by the valve 12 and, at a given moment, under the double action of the shortening of the lines of force and due to gradual upward movement of the core the diminution of the 90 weight of mercury being raised, the core is completely attracted. Hence, for a certain intensity there is a delay in the complete attraction, the delay becoming less as the intensity becomes greater. For a certain 95 intensity, attraction is instantaneous; that is, for an intensity which corresponds to one sufficient to attract the entire core unit comprising the cup and connected parts. The intensity of the current is controlled by the commutator 3, the co-efficient of instantaneous release by the mercury level which is itself controlled by the plunger 7, and the time by the opening left free at 11, the valve 12 being assumed to 100 be in closed position. The valve 12—13—14 renders it possible to effect the downward movement of the core unit without

delay, the valve 12 being removed from the opening 11 by the increased upward pressure of the mercury due to the release of the weight of the plunger and parts. At this time the mercury flows through the whole opening 11 and thus permits the rapid downward movement of the cup.

At a certain moment, the core, being under the influence of a number of ampere-turns, will cease to rise and an equilibrium will exist between the weight of the movable core unit and the force of attraction. Consequently, if the intensity starts to decrease and drops to normal, the core unit 15 must descend.

The outer part of the cup has been represented as having a cylindrical shape, but this is not essential; it can even be given a shape such as modifies at will the shape 20 of the curve traced by taking as abscissas the times of releasing and as ordinates the intensities. For example, by giving the cup the form indicated in Fig. 2, the release will be initially facilitated, since the layer 25 of mercury 15 is weaker than the layer 16; and the reverse can be effected.

The armature 4 and the cups 9 rise, as is above stated, when the intensity of the current is increased for a predetermined 30 time and a predetermined current and when they are so raised the upper portion 15 of the cup 9 engages at opposite sides with downwardly extending contact points 16 of binding posts 17 which are mounted in the 35 receptacle 5 and which are insulated therefrom as at 18. These binding posts are connected to an auxiliary circuit indicated by wires 19 so that when the cup 9 is in a predetermined raised position the circuit will 40 be closed.

I claim as my invention:—

1. A relay comprising a solenoid; a receptacle filled to a predetermined level with a dense fluid and located adjacent said solenoid; a vessel mounted within said receptacle and secured to the moving part of the solenoid to be raised thereby when a predetermined current passes through said solenoid, said vessel having a restricted opening 45 at its lower end through which said fluid may flow from the interior of the vessel to the interior of the receptacle and vice versa, means within said vessel for enabling the enlargement of said opening when the vessel 50 is descending into the fluid contained in the receptacle to permit a rapid descent of the vessel and the solenoid part with which it is connected; and contacts mounted on said receptacle and adapted to be closed when the 55 vessel is in raised position.

2. A time controller for an electric circuit closer comprising a receptacle filled to a predetermined level with a dense fluid; a vessel mounted in said receptacle for vertical 60 movement and having a passage at its lower 65

end whereby the interior of the vessel communicates with the interior of the receptacle and permitting the flow of the fluid contained in the receptacle to and from the vessel; means secured directly to the vessel 70 for imparting vertical movements thereto; and means within the vessel for partially closing said opening, said means being effective when the vessel is ascending to reduce the flow of fluid from said vessel to said receptacle and being rendered ineffective by an upward thrust imparted thereto by the fluid in the receptacle when the vessel is descending to permit a rapid descent of the 75 vessel.

3. A time controller for an electric circuit closer comprising a receptacle filled to a predetermined level with a dense fluid; a vessel mounted in said receptacle for vertical movement and having a passage at its lower 80 end whereby the interior of the vessel communicates with the interior of the receptacle and permitting the flow of the fluid contained in the receptacle to and from the vessel; means for partially closing said opening, said means being effective when the vessel is ascending to reduce the flow of fluid from said vessel to said receptacle and being rendered ineffective when the vessel is descending to permit a rapid descent of the 85 vessel; and means for adjustably varying the level of the dense fluid in said receptacle.

4. A time controller for an electric circuit closer comprising a receptacle filled to a predetermined level with a dense fluid; a vessel mounted in said receptacle for vertical movement and having a passage at its lower end whereby the interior of the vessel communicates with the interior of the receptacle and permitting the flow of the fluid contained in the receptacle to and from the vessel; means for partially closing said opening, said means being effective when the vessel is ascending to reduce the flow of fluid from said vessel to said receptacle and being rendered ineffective when the vessel is descending to permit a rapid descent of the 90 vessel; and means for adjustably varying the level of the dense fluid in said receptacle.

5. A time controller for an electric circuit closer comprising a receptacle filled to a predetermined level with mercury; a vessel 95 mounted in said receptacle for vertical movement and having a passage at its lower end whereby the interior of the vessel communicates with the interior of the receptacle; and a weighted float located in said vessel 100 and adapted to partially close said opening when the vessel is ascending in the receptacle to reduce the flow of mercury through said opening and retard the upward movement of 105 the vessel.

6. A time controller for an electric circuit closer comprising a receptacle filled to a predetermined level with mercury; a vessel mounted in said receptacle for vertical movement and having a passage at its lower end whereby the interior of the vessel communicates with the interior of the recep-

tacle; a tank for the mercury adjacent the receptacle and communicating therewith; and means for forcing the mercury from the tank into the receptacles for increasing the level of the mercury in the receptacle.

In testimony whereof I affix my signature.

EDOUARD VEDOVELLI.
